(57) **CLAIM**

We claim the ornamental design for a stapler, as shown and described.

DESCRIPTION

FIG. 1 is a right side view of the stapler showing our new design;

FIG. 2 is a left side view thereof;

FIG. 3 is a rear view thereof;

FIG. 4 is a front view thereof;

FIG. 5 is a top view thereof;

FIG. 6 is a bottom view thereof; and,

FIG. 7 is a perspective view thereof.

The broken lines showing various features in the drawings are for illustrative purposes only and those features form no part of the claimed design.
